(57) CLAIM

The ornamental design for a utility apron for work and personal supplies, as shown and described.

DESCRIPTION

FIG. 1 is a top perspective view of a utility apron for work and personal supplies, showing my new design in its environment;

FIG. 2 is a front elevation view thereof;

FIG. 3 is a bottom view thereof;

FIG. 4 is a rear elevation view thereof;

FIG. 5 is a top plan view thereof;

FIG. 6 is a right-side elevation view thereof; and,

FIG. 7 is a left side elevation view thereof.

The claimed design is shown with a symbolic break in its length. The appearance of any portion of the article between the break lines forms no part of the claimed design.

The ornamental design which is claimed is shown in solid lines in the drawings. The large broken lines in FIGS. 1-3 and 5-7 illustrate environment and form no part of the claimed design. The broken lines showing stitching is shown to represent an ornamental stitching pattern at the seams and forms part of the claimed design.
